UNITED STATES PATENT OFFICE.

FRANZ WIEDER, OF BLIERSHEIM, GERMANY, ASSIGNOR TO FRIED. KRUPP AKTIEN-GESELLSCHAFT, OF ESSEN-ON-THE-RUHR, GERMANY.

RAIL-FASTENING.

1,121,215.

Specification of Letters Patent.

Patented Dec. 15, 1914.

Application filed December 10, 1912. Serial No. 735,968.

To all whom it may concern:

Be it known that I, FRANZ WIEDER, residing at Bliersheim, Germany, a subject of the Emperor of Germany, have invented a certain new and useful Improvement in Rail-Fastenings, of which the following is a specification.

The subject matter of the present invention is a rail fastening intended for permanent ways with cross ties, in which only a single opening need be provided in the tie on the inside of the track, for the passing through of all the parts that serve to connect the rail with the tie; and this rail fastening is moreover distinguished by greater safety in running, combined with low costs of manufacture and maintenance.

One embodiment of the invention is illustrated in the drawing where, Figure 1 shows a central longitudinal section of the rail fastening; Fig. 2, a top plan view of Fig. 1 and Fig. 3 a section along 3—3 of Fig. 1 seen from the left.

The rail A rests by means of tie plates B on iron cross ties C. The rail is secured against lifting from the tie by means of a clamping piece D, which is fastened in usual manner by a bolt E with a rectangular head e¹. The clamping piece D engages with its projection d¹, the opening F provided for the bolt E at the inside of the track in the tie plate and the top of the tie, in order to prevent any inward displacement of the rail. The rail A is secured against outward displacement by means of a special hook shaped shoe G. This shoe rests in a recess b¹ of the tie plate B and fits tightly against the bottom face of the foot of the rail. It grips with a hook g¹ around the foot a¹ of the rail on the outside of the track, and with a hook g² under the top of the tie, on the inside of the track, this latter hook reaching down through the opening F.

The arrangement of the exchangeable shoe G has the advantage, that only the shoe, which is exposed to the greatest strain, need be manufactured from the best material, so that the cost of manufacture of the rail tie

in accordance with the present invention is only very small, although giving greater 50 running security. The same also applies to the cost of maintenance, as with eventual damage in most cases only the shoe but not the whole tie plate need be exchanged.

I claim:

55

1. Rail fastening for cross ties comprising a tie plate, a rail shoe and a clamping member; an opening in the cross tie and an opening in said tie plate registering with the cross tie opening, said shoe being constructed 60 as a double hook engaging the foot of the rail at one end and said openings at the other end to prevent outward displacement of the rail.

2. Rail fastening for cross ties comprising 65 a tie plate, an S-shaped rail shoe and a clamping member, said tie plate having an opening registering with an opening in the cross tie; a recess in said tie plate forming a seat for said shoe, one end of said shoe 70 engaging with one side, and said clamping member with the other side of the foot of the rail, the other end of said shoe engaging with said openings.

3. Rail fastening for cross ties comprising 75 a tie plate, a rail shoe and a clamping member, said tie plate having an opening registering with an opening in the cross tie; a recess in said tie plate forming a seat for said shoe; said shoe being constructed as a 80 double hook engaging the foot of the rail with one end and said openings with the other end.

4. Rail fastening for cross ties comprising 85 a tie plate, a rail shoe and a clamping member, said tie plate having an opening registering with an opening in the cross tie; a recess in said tie plate forming a seat for said shoe; said shoe being constructed as a double hook engaging one side of the foot 90 of the rail with one end and said openings with the other end; said clamping member constructed to engage the other side of the foot of the rail by means of one of its sides and with its opposite side to engage both 95 with said tie plate and in said opening of

the cross tie; said clamping member having a clamping bolt with a rectangular head reaching through the opening of and gripping the under side of the top of the cross tie and drawing the several parts together for preventing side displacement of the rail on the cross tie.

The foregoing specification signed at Bar-
men, Germany, this 19th day of November,
1912.

FRANZ WIEDER. [L. S.]

In presence of—

HELEN NUFER,

ALBERT NUFER.
